FREDRICK WILLIAM KASSLER, OF ST. LOUIS, MISSOURI, ASSIGNOR OF ONE-HALF TO ISIDOR WAGNER, OF ST. LOUIS, MISSOURI.

COIN-CONTROLLED LOCK.

No. 902,086.

Specification of Letters Patent.

Patented Oct. 27, 1908.

Application filed July 8, 1907. Serial No. 382,581.

To all whom it may concern:

Be it known that I, FREDRICK WILLIAM KASSLER, a citizen of the United States, and a resident of St. Louis, in the State of Missouri, have invented a new and Improved Coin-Controlled Lock, of which the following is a full, clear, and exact description.

My invention relates to coin-controlled locks, my more particular object being to produce a type of lock possessing certain advantages of construction and operation, and especially suitable for use in connection with a public telephone booth.

Reference is had to the accompanying drawings forming a part of this specification, in which similar characters of reference indicate corresponding parts in all the figures.

Figure 1 is a front elevation of my lock and its accompanying parts as seen from the exterior of a telephone booth; Fig. 2 is a section upon the line 2—2 of Fig. 3, looking in the direction of the arrow, and showing the two revoluble stems for manipulating the lock under different conditions from different sides of the door, and also showing the relative arrangement of various arms operated directly or indirectly from the revoluble stems, this view further showing the general arrangement of various parts and a removable closure plate for permitting access to the lock when the mechanism of the latter is out of order; Fig. 3 is an elevation showing the mechanism of the lock as viewed from the side thereof representing the inside of the booth, the inner plate of the lock being removed, and one of the stems being shown in section, this view showing the parts occupying their respective normal positions, the door being locked; Fig. 4 is a view substantially similar to Fig. 3, the parts occupying their respective positions assumed when the door is unlocked; Fig. 5 is a fragmentary section showing the arrangement of the main bolt and means whereby this bolt is controlled by aid of a coin; Fig. 6 is a substantially vertical section on the line 6—6 of Fig. 1 through a keeper forming a part of my improved lock, the keeper being so arranged that the door may be opened independently of the condition of other parts of the lock. Fig. 7 is a fragmentary section through the keeper and shows how the key fits upon the various tumblers; and Fig. 8 is a perspective of the

main bolt which is provided with a slot in which a coin may be temporarily housed.

At 9 is a fragmentary representation of the door of a telephone booth. The lock casing is shown at 10 and is provided with a horizontal portion 10^a. A removable closure plate 11 is provided at its bottom with lugs 12 which pass through the thickened portions 13 in the casing 10. This closure plate is further provided at its top with a lock 14 having a bolt 15. The latter engages a lug 16 and normally prevents the removal of the closure plate 11 from the casing. By aid of a key inserted through a fitting 17, however, the bolt 15 may be withdrawn within the lock 14. The closure plate 11 then may be taken out for the purpose of enabling a properly authorized person to open the casing in order to remove any coins deposited therein.

The main bolt is shown at 18, and has oppositely disposed bevels 18^a and 18^b. It is provided upon its upper surface with a toothed rack 19 having a lug 20 integral therewith. A pawl 21 having substantially an arcuate form is pivotally mounted upon the casing in the neighborhood of the rack 19, said pawl being double-ended as shown. A leaf-spring 22 is connected with the upper portion of the casing and depends into close proximity with the pawl 21. This leaf-spring co-acts with the pawl and serves to hold the latter in an approximately determinate position. Whenever the bolt 18, and consequently the rack 19, move to the left, according to Figs. 3 and 4, the pawl 21 successively engages the teeth of the rack and finally the lug 20 causes the pawl to rock so that its outer end passes below the lower end of the leaf-spring 22. The pawl remains in this position until, by a movement of the bolt 18 in the opposite direction, the lug 20 passes to the right and causes the pawl to rock to the left or in a "contraclockwise" direction, according to Figs. 3 and 4. When this engagement occurs between the lug 20 and the pawl, the rack 19 is moved so far to the right that the inner end of the pawl is unable to lock into any of the teeth, except the end tooth at the extreme left, as shown in Fig. 3. By this arrangement, whenever the lug 20 has made its extreme movement to the left according to the view shown in Figs. 3 and 4 and the pawl has correspondingly been changed in its position, owing to

its engagement with the lug 20, the pawl cannot prevent the return of the main bolt 18 to the right. On the other hand, however, if the main bolt 18 has only made a 5 partial movement toward the left so that the pawl engages in the teeth of the rack 19, the main bolt cannot be shifted to the right until the stroke of the main bolt is completed to the left or the pawl dislodged 10 by some other means than the lug 20. A plate 23 extends upwardly upon one edge of the main bolt 18 and serves as a slide-way for said bolt.

A lug 24 is cast integral with the casing 10, and is provided with a half-round projection 24^a serving as a limiting stop for one of the movable parts hereinafter described.

At 25 is shown a coin which may be used for operating the coin-controlled mechanism. The casing is provided with a slot 10^b through which this coin may be inserted by hand. The main bolt 18 is provided with a slot 26 for receiving the coin when the latter drops down into such position as to rest upon 25 the upper surface of the lug 24 (see Fig. 5).

A baffle plate 27 is connected rigidly with the casing. A coin chute 28 is provided with a projecting portion 29 serving as a measuring passage for defective coins. This projection 29 extends outwardly from the coin chute at an angle. The coin chute is pivotally mounted upon a screw 28^a in order that it may be tensioned, and is normally held in a predetermined position by a spring 30 for 35 this purpose. The coin chute is thus adapted to be swung upon the pivot 28^a whenever occasion requires, as, for instance, when the operator opens the casing for the purpose of dislodging a coin of improper size from 40 the coin chute. A pin 31 serves as a limiting stop for the coin chute, and normally the spring 30 causes the coin chute to exert a slight pressure upon this pin. If a coin of proper size be inserted, it will slide down 45 the chute, encounter the projection 29, and turn into a different plane (see Fig. 5).

A spiral spring 32 is connected with the main bolt 18 which is provided with an ear 33 for this purpose. The opposite end of 50 this spiral spring engages a bracket 34. A lug 35, cast upon the internal surface of the casing, serves as a limiting stop for preventing excessive movement of the main bolt 18.

An arm 36 is loosely mounted upon a rocking stem 37 and is provided with a lug 36^a extending laterally from the arm, as indicated in Fig. 2. The upper end of the arm 36 carries a pin 38 which projects into a slot 39 in the downwardly-projecting portion 40 of a slide 41. The slide 41 normally occupies such position that coins may be inserted through the coin slot, but whenever the arm 36 is moved into the position indicated in Fig. 4, the slide 41 is forced to the left and 60 thus closes the coin slot so as to exclude the

entrance of coins thereinto. The slide 41 is mounted within a slideway 42.

A leaf-spring 43 is provided upon its inner surface with a bevel or hook 43^a, these parts together serving as a spring latch and 70 being adapted to engage the arm 36 so as to hold the same in its extreme position to the left, according to Fig. 4. When the arm 36 is moved into the position indicated in this figure, the latch automatically secures it and 75 holds it until released, as hereinafter described.

A rocking stem 44 is provided with a button 45 serving as a knob. This stem is in alignment with the stem 37. Secured rigidly 80 upon the stem 37 and extending upwardly therefrom is an arm 46. This arm is connected with a spring 47 and drawn thereby to the right, according to Figs. 3 and 4. The arm 46 carries a lug 48 integral therewith 85 and projecting laterally therefrom partially into the path of the latch. The idea is that when the arm 46 is rocked to the left, according to Fig. 4, the lug 48 may engage the bevel or hook 43^a of the latch, thereby pressing the latch outward and disengaging it from the arm 36. The lug 48 serves another purpose, to wit: It engages the arm 36 and forces the latter to the left or into the position indicated in Fig. 4. It follows, therefore, that the arm 46 is used both in carrying the arm 36 to the left and in releasing this arm from its extreme position to the left.

A lug 49 integral with a panel 49^a serves as a limiting stop for an arm 50. A spring 100 51 tensions this arm and normally holds it in engagement with the lug 49, as will be understood from Fig. 4. A plate 52 entirely disconnected from the casing 10 is mounted at a point adjacent thereto, as will be understood 105 from Fig. 1.

A box 53 is mounted upon a pivot 54 and adapted to swing relatively to the plate 52. The upper end of the box 53 is comparatively thin and passes beneath a lug 55. Mounted 110 upon the thin upper portion of the box is a sleeve 56 provided with a slot 57. A key 58, detachable from all other parts, is provided with a boss 59 adapted to loosely enter the slot 57. A fitting 60 is provided with a number of tumblers 61, connected by a pin 63 and held in position by springs 62. The key 58 is adapted to fit upon the tumblers 61 so as to press the same out to the right, according to Fig. 6. Whenever the key 58 is inserted 115 and the tumblers depressed accordingly, the box 53 may be swung upon the pivot 54, the key being pressed so hard as to prevent the bodily movement of the key relatively to the plate. A person having a key may therefore 120 secure entrance to the booth independently of the condition of the lock. A button 64 is mounted rigidly upon the stem 37 and is used for manipulating the lock from the inside of the booth.

The operation of my lock is as follows: Suppose the parts to be in their normal positions, as indicated in Fig. 3. A person comes along and passes a coin 25 through the coin slot 10^a. If the coin is too small it will pass through the opening in the coin chute 29; if too large, it will not enter the slot. Assuming the coin to be a proper one, it glides downwardly and is baffled to the left and to the right, according to Fig. 5, by the members 29 and 27, finally lodging upon the lug 24 and standing upon its edge, projecting partially upward through the slot 26. The person next grasps the button 45 and turns it to his right—that is in a so-called clockwise direction. The arm 50 being rigid upon the stem 44 now presses against the coin, and the latter being within the slot 26 causes the bolt 18 to be drawn into the casing, to such an extent that the pawl 21 clicks over the teeth of the rack 19 and stops against the last tooth of the series, as indicated in Fig. 4. The lateral movement of the coin under pressure of the arm 50, causes the coin to press against the lug 36^a and thus moves the arm 36 from its position indicated in Fig. 3 to its extreme left, as indicated in Fig. 4. This movement of the arm 36 draws the slide 41 to the left and thus closes the coin slot 10^a. The arm 36 upon reaching its extreme position to the left, according to Fig. 4, is secured temporarily by the spring latch consisting of spring 43 and hook 43^a. The person desiring to enter the booth now opens the door and walks in. If, while this person is inside, another person should attempt to drop a coin into the coin slot, he would find it impossible, owing to the temporary closure of the slot by the slide 41. The arm 36 having been secured by the latch, relaxation of the button 45 or knob removes the pressure upon the coin and the latter thus drops into the bottom of the casing, the various movable parts of the mechanism, however, remaining for the time being, in their respective positions. The person inside the booth, after finishing conversation over the telephone, may now desire to leave the booth. He grasps the handle 64 (which extends inside the booth) and turns it toward his left, or in a counterclockwise direction. In doing this he causes the arm 46 to rock to the left. This brings the lug 48 against the bevel or hook 43^a and releases the same from engagement with the arm 36. The latter, under impulse of the spring 44, now moves to the right, according to Figs. 3 and 4. In doing this the slide 41 is restored to its normal position, thus leaving the slot 10^a uncovered and ready for the deposit of another coin. The same movement of the arm 46 causes it to slide the main bolt 18 to the left, thus enabling the person inside to open the door. The movement of the main bolt to the left being continued, the lug 20 tilts the pawl 21 in a clockwise direction, according to Figs. 3 and 4, thus freeing it from the rack 19. The leaf-spring 22 now prevents movement of the pawl into any position which will prevent the outward thrust of the main bolt 18. It will thus be seen that when a person is using the booth, it is impossible for any other person to lock him in or to interfere with him by depositing a coin or in any other way. It will also be noted that, as the bolt 18 has two bevels 18^a, 18^b, it must in any case recede within the lock whenever the door of the booth is opened or closed, and whenever the bolt thus recedes, it will release a coin if one be held in the lock. No matter, therefore, whether or not the operator works the knob or knobs properly when opening the door, the coin is always dislodged after every operation.

Having thus described my invention, I claim as new and desire to secure by Letters Patent:

1. In a lock, the combination of a coin chute, a main bolt provided with a slot for receiving a coin from said coin chute, an arm controllable by pressure of said coin when held within said slot, and means connected with said arm for preventing the entry of other coins into said coin chute while said bolt occupies a predetermined position.
2. In a coin-controlled lock, the combination of a coin slot through which coins may be dropped into the machine, a movable bolt provided with a portion for engaging said coins one at a time, means for closing said coin chute so as to prevent the entry of coins thereinto, and an arm connected with said means for actuating the same, said arm being provided with a lug projecting into the path of a coin engaging said bolt so as to turn said arm when said bolt is moved in a predetermined position.
3. The combination of a casing, a bolt slidable in relation thereto, an arm for actuating said bolt, a rocking stem connected with said arm for turning the same, a second arm mounted upon said stem, said second arm being loose relatively to said stem, a latch for holding said last-mentioned arm in a predetermined position, and means connected with said first-mentioned arm for releasing said second-mentioned arm, a coin chute, and a slide connected with said second-mentioned arm for opening and closing said coin chute.

In testimony whereof I have signed my name to this specification in the presence of two subscribing witnesses.

FREDRICK WILLIAM KASSLER.
